UNITED STATES PATENT OFFICE.

MARVIN G. THOMAS, OF BASIN, WYOMING.

PIPE.

1,111,196.

Specification of Letters Patent. Patented Sept. 22, 1914.

Application filed January 27, 1914. Serial No. 314,716.

To all whom it may concern:

Be it known that I, MARVIN G. THOMAS, a citizen of the United States of America, residing at Basin, in the county of Big Horn, 5 and State of Wyoming, have invented certain new and useful Improvements in Pipes, of which the following is a specification, reference being had thereto to the accompanying drawing.

10 This invention relates to pipes and has special reference to a device which is adapted to hold the two sections of a pipe in engagement with each other.

Another object of the invention is the production of a plurality of retaining members which are integrally connected so as to hold the same in their correct position upon a pipe.

With these and other objects in view, this 20 invention consists of certain new and novel combinations, constructions and arrangements of parts as will be hereinafter fully described and claimed.

In the accompanying drawings, Figure 1 25 is a side elevation of a pipe, showing my device attached thereto. Fig. 2 is an elevation of one of the sections of the pipe showing the retaining members carried thereby in section. Fig. 3 is a section taken on line 30 3—3, Fig. 1, looking in the direction of the arrow. Fig. 4 is a transverse section taken through the bowl of the pipe. Fig. 5 is a detail perspective view of one of the retaining members.

35 Referring to the drawings by numerals, 1 indicates the primary section of the pipe and 2 the auxiliary section. The primary and auxiliary sections are each provided with the usual bowl 3 having angularly-extending bodies 4 and 5. The body 4 is provided with the grooves 6, while the body 5 is provided with the ribs 7. The ribs 7 are adapted to fit within the grooves 6 for forming a tight closure between the bodies 4 and 40 5. The stem 8 is also formed of a plurality of sections having the usual groove and rib structure for allowing the same to be easily separated for cleaning, or for allowing the sections to be placed in engagement with

45 each other for forming a tight closure. The inner end of this stem 8 is provided with a large reduced neck 9 which is threaded into engagement with the bodies 4 and 5. In order to prevent the escaping of smoke 50 around the neck 9, a collar 10 may be placed

around the junction of the stem 5 and the bodies 4 and 5.

It will, of course, be obvious that the bodies 4 and 5 and the neck 8 are provided with the passages 11 and 11' which communicate with the bowl 3.

In order to hold the several sections of the pipe together, there is provided a primary retaining band 12 and an auxiliary retaining band 13. The primary retaining band 12 is 65 provided with a hinge 14 and clasp 15 whereby the same may be placed around the bowl 3 of the pipe and held firmly in engagement therewith. The auxiliary retaining band 13 is also provided with a hinge 16 and a clasp 70 17 for holding the same upon the bodies 4 and 5, and thereby holding these bodies in firm engagement with each other. In order to hold the primary and auxiliary retaining bands in their correct position upon a pipe, 75 there is provided a curved connecting finger 18 which is integrally formed upon the bands 12 and 13 as illustrated in Figs. 1 and 5. It will be seen that in this manner the bands will be held securely upon the pipe 80 and will be held at a spaced distance from each other. The stem 8 is also provided with the retaining rings 19 and 20 having the usual hinges 21 for allowing the same to be placed upon the stem 8. These rings 19 and 20 are also provided with a connecting link 22, thereby holding the same in spaced relation to each other upon the stem 8.

When this device is used, the several sections of the pipe may be placed in engagement with each other at which time the retaining bands 12 and 13 may be placed in their correct positions. By bringing the clasps 15 and 17 into engagement, the bands will be held in their correct position upon 95 the pipe. The rings 19 and 20 may then be placed upon the stem 8 whereby the several sections of the pipe will be held in firm engagement with each other.

From the foregoing description, it will be 100 seen that a simple and efficient means has been produced for holding the several sections of a pipe in detachable engagement with each other, and which is provided with efficient means for holding the retaining 105 members in spaced relation to each other upon the pipe.

What is claimed as new is:—

In a device of the class described, the combination with a pipe formed of a plurality of 110

sections, said pipe comprising a bowl and a body carried thereby, and a stem carried by said body, of a plurality of retaining bands positioned upon said bowl and said body,
5 said bands provided with hinged portions for allowing the same to be placed in their correct position, said bands also provided with clasps for allowing the same to be firmly held upon said bowl and said body;
10 an integral, curved finger formed upon said retaining band for holding the same in

spaced relation to each other and in their correct position upon the pipe, whereby said sections of said pipe will be held in firm engagement with each other.

15

In testimony whereof I hereunto affix my signature in presence of two witnesses.

MARVIN G. THOMAS.
